MODULATED ALARM CLOCK

Dudley S. Ingraham, Bristol, Conn., assignor to
 The E. Ingraham Company, Bristol, Conn., a
 corporation

Application April 18, 1934, Serial No. 721,145

12 Claims. (Cl. 58—16)

This invention relates to time instruments and more particularly to time instruments known as alarm clocks.

One object of this invention is to provide an improved alarm clock having means whereby the alarm may be adjusted to give different degrees or loudness in accordance with the sensitivity of wishes of the person using the clock.

Another object of this invention is to provide an improved alarm clock in which improved mechanism is provided for causing the loudness of the alarm to be varied automatically during an alarm-sounding period.

Another object of this invention is to provide an improved alarm clock in which the loudness of the alarm is automatically varied in a plurality of repeated cycles during a single alarm-sounding period.

With the above and other objects in view, this invention includes all improvements over the prior art which are disclosed in this application.

In the accompanying drawings in which certain ways of carrying out the invention are shown for illustrative purposes:

Fig. 1 is a rear elevation, on reduced scale, of an alarm clock illustrating one embodiment of the invention;

Fig. 2 is a vertical sectional view on line 2—2 of Fig. 1;

Fig. 3 is a rear elevation similar to Fig. 1, with part of the rear portion of the casing broken away;

Fig. 4 is a view similar to Fig. 3, with the movable sound-modulating plate shown in a different position;

Fig. 5 is a rear perspective view of the movable sound-modulating plate for closing and opening the sound-opening in the rear of the casing;

Fig. 6 is a rear elevation, with part of the rear portion of the casing broken away, of a modified form of sound-modulating mechanism;

Fig. 7 is a horizontal sectional view on line 7—7 of Fig. 6; and

Fig. 8 is a rear perspective view of the modified form of the movable sound-modulating plate shown in Fig. 6, for closing and opening the sound-opening in the casing.

In the description and claims, the various parts are identified by specific names for convenience, but they are intended to be as generic in their application as the prior art will permit.

Referring to the drawings, 10 indicates an alarm clock having a casing 11 mounted on a base 12, the rear of the casing 11 being provided

with a plurality of openings 13 forming a grating or sound-openings. 14 is a clock movement to which the bell or alarm-sounding member 15 is connected in supporting relation as shown.

The sound-modulating plate 16 (Fig. 5) has a plurality of openings 17 of suitable size and spacing to permit of their being placed in register with the openings 13 in the rear of the casing 11, or to be shifted to a non-registering position to bring the intermediate metal portions 18 into register with the openings 13 to close the latter.

The plate 16 is provided with a central opening 19 adapted for pivotal engagement on the center-arbor 20, the clearance-openings 21 being provided to permit the plate to clear various parts of the clock movement when the plate is oscillated in one or the other directions when in use. The resilient pressed-in portions 22 rest upon the rear movement-plate 23 and aid in providing a smooth movement to the plate 16 when it is oscillated in one direction or the other to open or close the sound-openings 13 in the rear of the casing. The upper portion of the plate is provided with a pin 24 fixed thereto and extending rearwardly through the slot 25 in the rear of the casing so as to provide manual means to be engaged to oscillate the plate 16. The ends of the slot 25 may serve to limit the oscillating movements of the pin 24 and plate 16.

Secured to the lower left inside face of the plate 16 is a yieldable sound-damping spring-arm or finger 26 which, when the plate 16 is oscillated about its pivot 19 in an anti-clockwise direction, causes the metal portions 18 to register with and close, or partly close, openings 13, depending on the amount of the movement given to the plate 16, and also causes the yielding finger 26 to engage against the bell or sounding-member 15 to modulate or decrease the loudness of the sound produced by the bell.

In the modified form of the invention illustrated in Figs. 6, 7 and 8, the coil-spring 27 illustrates the usual coil-spring for actuating 45 the striking-member 28 to cause the latter to repeatedly oscillate about its pivot 29 to strike the bell 15, in a well-known manner.

In this form of the invention, instead of employing a manually-oscillatable plate 16, a modified form of sound-modulating plate 30 is provided which has clearance-openings 21, a spring-finger 26, openings 17, metal portions 18 and a central pivot opening 19, all similar to corresponding parts on the plate 16.

Instead of providing for manual actuation of the plate 30, however, a pin 31 is extended inward in an opposite direction from the pin 24 of the plate 16, so as to be engaged by the 5 surface of a cam 32 mounted on an arbor 33 coaxially with the driven wheel 34 of a Geneva movement, having slots 35 adapted to be engaged and driven by a pin 36 carried by the driving-wheel 37 of the Geneva movement 10 mounted on the arbor 33 coaxially with the spring 27. A spring 39 is secured to the rear movement-plate 23 and presses against the arm 40 of the plate 30, to normally maintain the pin 31 in engagement with the cam 32.

15 In the form of the invention illustrated in Figs. 1 to 5, if it is desired to have the alarm produce its maximum degree of sound, the pin 24 is pushed to its limit in a clockwise direction to align the openings 17 and 13, and to 20 cause the spring-finger 26 to be out of contact with the bell 15, whereupon the alarm clock will function to produce a maximum degree of sound.

25 Where, however, one desires to reduce or modulate this sound, this can be accomplished in one of a number of desirable degrees by pushing the pin 24 in a counter-clockwise direction to either partly or wholly disalign the openings 17 and 13, and to lightly or heavily press the 30 spring-finger 26 against the bell 15 to modulate or reduce the sound produced by the bell, as may be desired by the person using the same. The resilient pressed-in portions 22, by engagement against the rear movement-plate 25, produce 35 friction therewith and also press the plate 16 into frictional contact with the rear of the casing 11, thus providing ample friction to retain the plate 16 in any desired adjusted position.

40 In the form of the invention illustrated in Figs. 6 to 8, instead of the modulation of the degree of sound being accomplished manually, it is accomplished automatically. In the particular form of the invention illustrated, this 45 automatic modulation is brought about by means of the spring 27 acting through the Geneva movement previously described, to cause the cam 32 to push the pin 31 against the action of the spring 39, to cause the openings 17 and 13 to gradually become aligned. When the maximum height of the cam 32 starts to recede from the pin 31, the spring 39 pushes the arm 40 counterclockwise to cause the openings 17 to 50 gradually move to disalignment with the openings 13. The spring 27 and the parts which take part in oscillating the pin 31 can be so designed as to cause the pin 31 and plate 30 to oscillate in a plurality of cycles during a single unwinding of the spring 27.

55 The invention may be carried out in other specific ways than those herein set forth without departing from the spirit and essential characteristics of the invention, and the present embodiments are therefore to be considered in all respects as illustrative and not restrictive, and all changes coming within the meaning and equivalency range of the appended claims are intended to be embraced therein.

I claim:

70 1. An alarm clock including: a casing; an alarm-sounding member in the casing; the casing having a sound-opening for transmitting sound from the alarm-sounding member; and movable means mounted to move in a plane substantially parallel to the plane of the sound-

opening for closing or opening said sound-opening.

2. An alarm clock including: a casing; an alarm-sounding member in the casing; the casing having a sound-grating for transmitting sound from the alarm-sounding member; and movable means mounted within said casing and to move in a plane substantially parallel to the plane of the sound-grating for closing or opening said sound-grating. 10

3. An alarm clock including: a casing; an alarm-sounding member in the casing; the casing having a sound-opening for transmitting sound from the alarm-sounding member; movable means for closing or opening said sound-opening; and a sound-damping member actuated to engage said sounding-member when said movable means is moved to close said sound-opening. 15

4. An alarm clock including: a casing; an alarm-sounding member in the casing; the casing having a sound-opening for transmitting sound from the alarm-sounding member; movable means for closing or opening said sound-opening; and a sound-damping member carried 25 by said movable means to engage said sounding-member when said movable means is moved to close said sound-opening.

5. An alarm clock including: a casing; an alarm-sounding member in the casing; the casing having a sound-opening for transmitting sound from the alarm-sounding member; movable means for closing or opening said sound-opening; and a yieldable sound-damping member carried by said movable means to engage 30 said sounding-member when said movable means is moved to close said sound-opening. 35

6. An alarm clock including: a casing; an alarm-sounding member in the casing; a striking-member for striking the sounding-member; a motor for actuating the striking-member; and a sound-damping member actuated by said motor to cause said sound-damping member to move to and away from damping engagement with said alarm-sounding member. 40

7. An alarm clock including: a casing; an alarm-sounding member in the casing; a striking-member for striking the sounding-member; a motor for actuating the striking-member; and a sound-damping member actuated by said 50 motor to cause said sound-damping member to move in a cycle to and away from damping engagement with said alarm-sounding member.

8. An alarm clock including: a casing; an alarm-sounding member in the casing; a striking-member for striking the sounding-member; spring-windable motive means for actuating the striking-member; and a sound-damping member actuated by said motive means to cause said sound-damping member to move in a cycle repeated a plurality of times during a single unwinding of said spring, to and away from damping engagement with said alarm-sounding member. 55

9. An alarm clock including: a casing; an alarm-sounding member in the casing; the casing having a sound-opening for transmitting sound from the alarm-sounding member; a striking-member for striking the sounding-member; motive means for actuating the striking-member; and movable means mounted to move in a plane substantially parallel to the plane of the sound-opening and actuated by said motive means to cause said movable means to close and open said sound-opening. 65

10. An alarm clock including: a casing; an alarm-sounding member in the casing; the casing having a sound-opening for transmitting sound from the alarm-sounding member; a 5 striking-member for striking the sounding-member; spring-windable motive means for actuating the striking-member; and movable means actuated by said motive means to cause said movable means to close and open said 10 sound-opening in a cycle repeated a plurality of times during a single unwinding of said spring.
11. An alarm clock including: a casing; an alarm-sounding member in the casing; the casing having a sound-opening for transmitting 15 sound from the alarm-sounding member; a striking-member for striking the sounding-member; motive means for actuating the striking-member; and movable means and sound-damping means both actuated by said motive 20 means to cause said movable means to close and open said sound-opening, and cause said sound-damping means to move to and from sound-damping engagement with said alarm-sounding member.
12. An alarm clock including: a casing; an alarm-sounding member in the casing; the casing having a sound-opening for transmitting sound from the alarm-sounding member; a striking-member for striking the sounding-member; spring-windable motive means for actuating the striking-member; and movable means and sound-damping means both actuated by said motive means in a cycle repeated a plurality of times during a single unwinding of said spring to cause said movable means to close and open said sound-opening, and cause said sound-damping means to move to and from sound-damping engagement with said alarm-sounding member.
